MATERIAL HANDLING MECHANISM

Earl J. Woltz, Columbus, Ohio, assignor to The Jeffrey Manufacturing Company, a corporation of Ohio

Application June 22, 1938, Serial No. 216,317

6 Claims. (Cl. 209—399)

This invention relates to a material handling mechanism and more particularly to a dewatering screen structure including readily removable screen pans.

5 An object of the invention is to provide a simple dewatering screen structure in which screen pans may be readily removed and which will prevent troughing along the edges thereof.

Another object of the invention is to provide a 10 simple removable screen pan.

Still another object of the invention is to provide a simple but effective frame structure for a dewatering screen adapted to receive removable screen pans.

15 Other objects of the invention will appear hereinafter, the novel features and combinations being set forth in the appended claims.

In the accompanying drawings,

Fig. 1 is a side elevational view showing an 20 installation comprising my invention with a sludge tank shown in section;

Fig. 2 is a transverse sectional view taken on the line 2—2 of Fig. 1 looking in the direction of the arrows;

25 Fig. 3 is an oblique view of an enlarged section of the screen;

Fig. 4 is an enlarged view of a detail showing a portion of the frame structure; and

Fig. 5 is a sectional view of a detail of Fig. 4 30 showing also the pan mounting.

Referring particularly to Fig. 1 of the drawings, there is illustrated a superstructure 10 from which is suspended a double deck dewatering screen 11, by means of wood hang rods 12. The dewatering screen 11 comprises a pair of upper longitudinally extending channels 13, 13 and a pair of bottom longitudinally extending angles 14, 14 which are connected together at their ends by rear side plates 15 and front side plates 16. The lower flange of each channel 13 is severed 40 at spaced intervals so that intermediate the front side plates 16 and rear side plates 15 there are provided upstanding connecting angles 17, 17 (see Fig. 2), which are riveted to members 13, 13 and 14, 14 and are in transverse alignment with the hang rods 12. The members 13, 13 and 14, 14 are connected together by angle cross-pieces 45 to maintain said members 13, 13 and 14, 14 in predetermined lateral spaced relation. Brackets 50 18, 18 are rigidly attached to said hang rods 12, cross-pieces 45 and connecting plates 17 as by bolts 44 to effect the aforementioned suspension of the double deck dewatering screen 11 from the superstructure 10. Brackets 46, 46 riveted to cross-pieces 45 and channels 13, 13 reinforce the

connection between them. It may be stated that the hang rods 12 are preferably made of wood because of the resiliency of this material which results in a relatively long life of said hang rods.

Oscillatory movement of the double deck dewatering screen 11 is provided by means of an electric motor 19, reduction drive mechanism 20 and pitman 21. Material, such as cleaned coal, containing an appreciable amount of water coming from a gravity separator, such as a jig, is fed 10 to the double deck screen 11 by way of feed chute 22. Material from the lower dewatering screens 11 is delivered to a scraper conveyor 23 while that from the upper of said screens is delivered to a similar scraper conveyor not shown 15 in the drawings.

By reference particularly to Figs. 2 and 3 of the drawings, it will be seen that the upper of said dewatering screens is formed by the channels 13, 13 which carry at spaced intervals inwardly 20 extending projections, pins or lugs 24 each formed by a rivet the head of which is welded to a bearing plate 25 (see Figs. 4 and 5) which bearing plate is in turn riveted to a channel member 13 with the pin 24 projecting through an opening 25 in said channel member 13 and extending inwardly thereof.

Forming the screening portion of said upper dewatering screen is a plurality of pans 26 each comprising bottom plate 27 having perforations 28 over substantially the entire surface thereof which may be of any desired size, such as from $\frac{3}{4}$ inch to $1\frac{1}{4}$ inch, to effect a sizing and dewatering of the coal received over the feed chute 22. The forward and rearward edges of each pan 26 are provided with downwardly extending integral reinforcing flanges 29 and the lateral edges thereof are provided with upwardly extending integral flanges 30, which flanges 30 make substantially a right angle with the plane of said bottom plate 27. At spaced intervals along said pan 26 and in alignment with the projections or lugs 24 are notches or slots 31 adapted to receive said projections or lugs 24. It is to be particularly noted that the notches or slots 31 are effected by removing material both from the bottom plate 27 and a flange 30. That is, said notches or slots 31 extend into both the bottom plate 27 and the flanges 30. This has two important results. In the first place it provides for the ready removal of the pans 26 by virtue of the fact that said pans can be removed substantially vertically and the slots or notches 31 will clear the innermost projections of the lugs 24.

Furthermore, it has been found in practice 55

that an effective angular trough is formed at the juncture between the lateral edge of the bottom plate 27 and the flange 30 if such juncture is longitudinally continuous. Such structure would 5 allow water to flow continuously down this angular trough and over the end of the dewatering screen when it should pass through said dewatering screen. It is manifest that the notches or slots 31 prevent any such continuous trough being 10 formed along the edges of the pans 26 and as a consequence insure the complete drainage of water therefrom. Thus not only has a very simple and effective removable support been provided for the pans 26 but this support also prevents 15 edge troughing of liquid.

The lower of the double deck dewatering screens is formed by the aforementioned angles 14 and removable pans 32 which are removably attached to said angles 14 by bolts 33 cooperating 20 with upstanding flanges on the lateral edges of the pans 32. It may be stated that the pans 32 are provided with relatively small perforations 34 since it is desirable that only the smallest sized material, such as sand, clay and wet coal 25 dust, pass through them with the water, but it is desirable that substantially all the water which comes over with the coal freely pass through said perforations 34. In practice, I frequently make the perforations 34 of herring bone design 30 of one inch by $\frac{1}{8}$ inch slots, so as to have the desirable screening action.

Positioned below the double deck dewatering screen 11 is a trough or sluiceway 35 which catches the water and fine material, such as fine 35 coal, sand and clay carried with it through said screen pans 32, and delivers it to the primary cell 36 of a sludge tank 37 where the fine coal, sand and clay are allowed to settle for removal by a conveyor 38 in the primary cell and a conveyor 39 in the final settling tank. It may be 40 stated that the primary cell 36 is separated from the rest of the settling tank by a distribution baffle 40 formed by a plurality of spaced upright members relatively closely positioned to require a relatively uniform flow of liquid therethrough.

Furthermore, to prevent the surging of liquid 45 down the trough or sluiceway 35 and into the primary cell 36 the sloping portion 41 thereof is preferably formed with perforations or provided with a screen to allow a portion of the water to flow therethrough.

Still further, the forward upright plate 42 of the discharge chute 43 associated with said trough or sluiceway 35 is likewise perforated or provided with a screen to break up the liquid flow 50 and to prevent surging of liquid in said primary cell 36.

These features of the trough or sluiceway 35 and of the sludge tank 37 are the invention of 55 Max A. Matthews.

In the operation of the apparatus comprising my invention the double deck dewatering screen is reciprocated by the motor 19, drive mechanisms 20 and 24, while the material, such as coal, containing an appreciable amount of water as received from a jig is fed at the upper end thereof and flows downwardly thereacross. The water and material capable of passing through the perforations 28 in the screen pans 26 will flow 60 therethrough and onto the screen pans 32. Material incapable of passing through said perforations 28 flows down said pans 26 and onto the receiving conveyor 23. At the same time there is an assurance that water which tends to flow 65 down the longitudinal corners of the pans 26 will

be drained therefrom by means of the notches or slots 31.

Substantially all of the coal which passes through perforations 28, except for the very fine material, will flow down the pans 32 into the receiving scraper conveyor 23. The water, carrying with it very fine coal, clay and sand, passes through the perforations 34 and is received by the trough or sluiceway 35 by which it is directed to the sludge tank 37, being first received in the 10 primary cell 36 thereof and being delivered there- 15 to after being broken up, particularly by the screens at 41 and 42, to prevent surging. The fine coal, clay and sand settles from the water in the sludge tank 37 by which it is removed by 15 conveyors 38 in a manner well understood in this art.

It is thus evident that I have provided a dewatering screen in which the pans are readily removable by virtue of very simple supporting 20 means, which means also operates to prevent edge troughing of the liquid.

It may be stated that the removable feature of pans 26 is extremely desirable to the end that pans with different size openings or perforations 25 28 may be substituted, thereby varying the size range of the coal received by the conveyor 23 and delivered over the discharge end of the upper dewatering screen. This makes for a very flexible type of dewatering screening apparatus 30 which also acts as a controllable sizing screening means adapted for use in a tipple to deliver varying size ranges to different conveyors and to different coal cars, free of the clay, fine sand and water adhering to the coal after leaving the 35 jig or other coal separating apparatus.

Obviously those skilled in the art may make various changes in the details and arrangement of parts without departing from the spirit and scope of the invention as defined by the claims 40 hereto appended, and I therefore wish not to be restricted to the precise construction herein disclosed.

Having thus described and shown an embodiment of my invention, what I desire to secure 45 by Letters Patent of the United States is:

1. A dewatering screen comprising a frame formed by spaced side members, a removable perforated pan extending between said side members, means for supporting said pan on said side members for ready removal comprising supporting pins extending inwardly of said side members, said pan having upstanding side flanges provided with pin receiving notches which continue laterally into the pan bottom to permit vertical movement of said pan on and off said pins, said notches also providing water draining means at the angular edges formed by said pan bottom and side flanges to prevent water troughing along said edges.

2. A screen comprising a frame, a removable pan carried by said frame, said pan having a bottom and a side flange, pan supporting lugs on said frame, said pan bottom and side flange being provided with a pin receiving slot which extends continuously from the pan bottom into the side flange for supporting said pan on said frame and provides for vertical movement of said pan on and off said lugs.

3. A screen comprising a frame, a readily removable pan mounted thereon having a bottom and a side flange forming an angular edge, means for removably supporting said pan including projecting means on said frame, said pan having a projecting means receiving slot at said angular 70 75 80 85 90 95 100 105 110 115 120 125 130 135 140 145 150 155 160 165 170 175 180 185 190 195 200 205 210 215 220 225 edge which slot extends into both said pan bottom and said side flange and provides for vertical movement of said pan on and off said projecting means.

5. 4. In a dewatering screen, the combination with a frame formed of spaced members carrying inward projections, of a removable perforated pan comprising a bottom plate and integral upwardly extending side flanges forming angles, 10 said angles being slotted to receive said projections by continuous slots which cut into both said bottom plate and said side flanges and provide for vertical movement of said pan on and off said projections.

15. 5. In a device of the class described, the combination with a frame having inward projections,

of a pan mounted on said frame and formed of a bottom plate and upstanding side flanges, and slots for receiving said projections and extending into said bottom and said side flanges and provide for vertical movement of said pan on and off said projections. 5

6. A dewatering screen pan comprising a perforated bottom plate having upstanding side flanges forming angles with said bottom, and support forming slots at said angles extending into 10 said flanges and said bottom, said slots being adapted to receive supporting lugs which extend into them and to provide for vertical movement of said pan on and off said supporting lugs.
